BY

Gardner D. Pearson

ATTORNEY.

UNITED STATES PATENT OFFICE.

SAMUEL ROSENBLUM, OF LOWELL, MASSACHUSETTS.

AUXILIARY SPRING ATTACHMENT FOR SPRING BED BOTTOMS.

Application filed November 17, 1922. Serial No. 601,627.

To all whom it may concern:

Be it known that I, SAMUEL ROSENBLUM, a citizen of Lithuania, residing at Lowell, in the county of Middlesex and State of Massachusetts, have invented certain new and useful Improvements in Auxiliary Spring Attachments for Spring Bed Bottoms, of which the following is a specification.

My invention relates to auxiliary spring attachments for spring bed bottoms. It may be used with metal beds to which woven wire bed bottoms are directly attached or to any type of beds wherein the main springs are removable from the bed frame.

It may also be used with the type of spring bed bottoms wherein helical springs extend from head to foot.

Where these types of bed springs are used there is a tendency to sag in the middle where the weight comes, and this tendency increases with use as the springs stretch and become weaker.

My attachment is entirely separate from the bed and main springs, and is intended to be sold separately and is of such construction that the purchaser can readily put it in place in such position that it will best counteract the sagging of the main springs. It can also be adjusted to some extent vertically and is also arranged so that when anyone sits on the side of the bed, auxiliary springs allow of giving thus relieving the helical springs.

These auxiliary springs help to equalize any sudden shock, and help to absorb it without disturbing the other part of the bed. By their use two persons of different weights can sleep in the same bed without inconveniencing each other.

In the drawings, Figure 1 is a plan view of a metal bedstead of well known construction with the head board and foot board cut off and mattress removed to expose removable springs of a well known type where the body of the spring is made of crossed wires with tension springs at each end.

Fig. 2 is a bottom view of my auxiliary spring attachment removed from the bed, some parts being broken away to show the construction above.

Fig. 3 is a sectional elevation on the line 3-3 of Fig. 1 looking in the direction of the

arrow, but showing part of the mattress in place.

Fig. 4 is a side elevation showing part of a bed frame with my device in position.

Fig. 5 is a detail sectional elevation showing one of the dogs and supports on a larger scale than shown in Fig. 3.

Fig. 6 is a detail sectional elevation showing the adjusting bolt and nut for one of the dogs.

Fig. 7 is a view similar to Fig 5 showing modified construction of dog.

In the drawings, 1 represents the floor on which rests a metal bed A having legs 16, 16, 16, 16, side rails 10, 11, and the usual cross bars 14 and 15 at the head and foot.

The main spring bed bottom is represented by B and includes side bars 20 and 21, shown as of the common tubular type with the connecting head bar 22 and foot bar 23. The woven fabric 24 is of a well known type and is elastically connected with the head bar and foot bar by tension springs 25. The bed and springs are of a well known type.

My device, indicated generally by C, includes parallel spacing bars 30 and 31 having a guide rod hole 32 extending vertically through each bar near each end and having an adjusting slot 35 also located near the end of each bar. These bars are shown as being preferably formed of metal angle irons to secure rigidity.

Bars 30 and 31 are supported at each end by a supporting dog D having bolt holes 40, 40 through which pass adjusting bolts 44, 44 on the end of which are winged nuts 45, as shown in Fig. 6. By means of slot 35 holes 40, bolts 44 and nuts 45, these dogs can be slid in and out as shown by the dotted lines in Fig. 5 for convenience in adjusting in position.

Each dog has a lower jaw 41 and an upper jaw 42, which latter preferably terminates in a nose 43 which, when in position, extends over and rests upon a side rail 10 or 11 of the bed A in case the main springs B are removable. In any event the jaws 41 and 42 fit around a side bar 20 or 21 and hold my attachment C in the desired position.

I may use in connection with each dog a set screw 46 which passes through one of the jaws and bears against a bar 20 or 21 whereby my device can be shipped with the

main springs and held firmly in position against sliding.

E represents a rigid bottom frame comprising side members 50, 51 and front and back members 52 and 53, connected at the corners by braces 54 to make it rigid. Through this frame are rod holes 55, 55, 55, 55 which register with the guide rod holes 32, 32, 32, 32 in the bars 30 and 31.

10 Extending down through each rod hole 55 is an adjustable guide rod 81 on which are clamping nuts 82 and 83, thence down through a hole 32, each such rod being adjustably held in position extending down 15 from frame E by adjusting nuts 82 and 83 and by winged nut 84.

Preferably, surrounding each rod is an auxiliary compression spring 80. These springs 80 tend to keep my device up against 20 the bed bottom but it can readily be lowered against these springs or raised by screwing up or down nut 84.

F represents the top frame which may be rigid or, preferably, semi-rigid. It is 25 shown as formed by means of a relatively heavy rectangular wire 60, between the sides of which extend the lighter wires 61 to hold it from distorting. The helical springs 70, 70 are carried by the bottom frame E and 30 support the top frame F, being attached to wires 60 and 61 in such manner that they will not tear the mattress.

Preferably, they are so positioned and arranged as to form a hollow rectangle whereby 35 by a substantial space of perhaps six to twelve inches is left between the front and back rows 71, 72, while the side rows are filled in by springs 73, 74.

The effect of this arrangement is to 40 stiffen up the sides of the bed but to leave a relatively soft but firm section between 71 and 72.

I prefer to bend up the wire 60 of top frame F at each side, as shown in Figs. 4 45 and 5, to hold at 90 and 91 mattress M in position, and to use connecting wires, such as 92, to maintain the rigidity.

To put in place, the dogs D on one side 50 may be slid back and the device pushed up from under the bed, or slid in between fabric B and a bar 20 or 21, and the dogs slid out to engage said bars where they can be clamped in position by nuts 45.

In Figs. 7, I show how a modification of 55 my structure can be used as with a bed in which the side rails, such as 10 and 11, and side bars, such as 20 and 21, are combined as in a tubular side bar such as S.

In this case, I make the dogs, such as 105, 60 integral with the spacing bar such as P, such spacing bar having a vertical web 100 and horizontal web 101 with a rod hole 102.

The dog 105 has only an upper jaw and simply rests on bar S.

65 E represents the bottom frame with a

member 53 the same as in the other construction, and with a rod hole 55 through which passes a rod 106 which also passes through rod hole 102.

As shown, there are two clamping nuts 70 82 and 83 to hold it rigidly to frame E and two clamping nuts 103 and 104 to hold it rigidly to the spacing bar P.

I claim:

1. The combination with a bed having 75 side rails and a spring bed bottom having side bars, of an auxiliary spring attachment including parallel spacing bars having guide rod holes and adjusting slots, supporting dogs slidable on said spacing bars and having bolt holes which register with the adjusting slots and jaws which engage the side bars, the upper jaw having a nose which engages 80 a side rail, adjusting bolts which pass through said bolt holes and adjusting slots, winged nuts for said adjusting bolts, adjustable guide rods which extend from the rigid bottom frame downwardly and pass 85 through the rod holes in the spacing bars, auxiliary compression springs each surrounding a guide rod between a spacing bar and the bottom frame, a top frame bent up at each side to form a mattress holder, and helical springs carried by the bottom frame and supporting the top frame so positioned 90 as to form a hollow rectangle.

2. The combination with a bed having 95 side rails and a spring bed bottom having side bars, of an auxiliary spring attachment 100 including parallel spacing bars having guide rod holes and adjusting slots, supporting dogs slidable on said spacing bars and having bolt holes which register with the adjusting slots and jaws which engage the side bars, the upper jaw having a nose which engages 105 a side rail, adjusting bolts which pass through said bolt holes and adjusting slots, winged nuts for said adjusting bolts, adjustable guide rods which extend from the rigid bottom frame downwardly and pass 110 through the rod holes in the spacing bars, auxiliary compression springs each surrounding a guide rod between a spacing bar and the bottom frame, and helical springs carried by the bottom frame and supporting 115 the top frame so positioned as to form a hollow rectangle.

3. In an auxiliary spring attachment for 120 spring bed bottoms, the combination of parallel spacing bars having guide rod holes and adjusting slots, with supporting dogs 125 slidable on said bars and having bolt holes, adjusting bolts which pass through said bolt holes and adjusting slots, winged nuts for said adjusting bolts, a rigid bottom frame having downwardly projecting adjustable guide rods which pass through the rod holes in the spacing bars, winged nuts therefor, auxiliary springs between the spacing bars and bottom frame, a top frame, and helical 130

springs carried by the bottom frame and supporting the top frame positioned to form a hollow rectangle.

4. In an auxiliary spring attachment for spring bed bottoms, the combination of parallel spacing bars having guide rod holes, with supporting dogs on said bars, a rigid bottom frame having downwardly project-

ing adjustable guide rods which pass through the rod holes in the spacing bars, auxiliary springs between the spacing bars and bottom frame, a top frame, and helical springs carried by the bottom frame and supporting the top frame positioned to form a hollow rectangle.

SAMUEL ROSENBLUM.
